DEFLECTOR FOR INFANTS' TOILET SEATS

Michael Feldstein, Philadelphia, Pa.

Application October 13, 1948, Serial No. 54,271

2 Claims. (Cl. 4—239)

1

The present invention relates to toilet seats and attachments therefor, and more particularly to deflectors or splash-shields for toilet seats used by infants.

An object of the present invention is to provide a potty-chair or stool or the like for infants which embodies a disappearing splash-shield or deflector therein.

Another object of the present invention is to provide an infant's potty-chair or stool which has incorporated therewith a splash-shield or deflector which is concealed within the stool or chair or the like when the potty-chair is not in use.

Another object of the present invention is to provide a covered potty-chair or stool with a splash-shield or deflector so designed and constructed that the said shield is concealed when the stool is not in use but which will be properly positioned and immediately ready for use when the cover of said stool is raised.

An additional object of the present invention is to provide a splash-shield or deflector for use with an infant's covered potty-chair which need not be manually positioned or disposed for use with said potty-chair, but which splash-shield is independently and automatically disposed for use when the chair-cover is raised.

Further objects of the present invention will be readily discernible by reference to the appended specification, claims and drawings.

The idea of attaching a cup-shaped deflector or splash-shield to an infant's toilet-training device or to an infant's seat-cover (adapted for use with a toilet bowl intended for adult use), is not new. Prior patents have disclosed the broad idea of attaching a deflector of one sort or another to an infant's training-seat so that the larger adult toilet-bowl can be used alternately by adults or infants.

None of these prior patents disclose a splash-shield particularly adapted for use with an infant's potty-chair. A potty-chair can be distinguished from an infant's toilet-training seat in that the toilet-training seat is adapted for use on an adult-size toilet-bowl, whereas an infant's potty-chair or seat includes an independent chair, manufactured on a reduced scale so as to be conveniently available to small children, and which also includes an independent bowl or receptacle. A potty-chair or stool is readily transportable and has the added feature of being available for use by infants without the necessity of adult assistance, which is necessary when

2

a training-seat is used in cooperation with an adult toilet-bowl.

In addition, a novel feature of the present invention resides in the splash-shield or deflector which is automatically adjusted for use when the stool-cover is raised for use. This feature permits the entire stool to be instantly available to infants without the necessity for training the youngster to position the deflector or the necessity of having an adult supervise preparation of the potty-chair.

It is thus contemplated that the present invention will provide a sanitary and convenient toilet-bowl for use by infants which insures a maximum of protection and a minimum of care, operation or guidance on the part of the parent.

For the purpose of illustrating the invention, there are shown in the accompanying drawings forms thereof which are at present preferred, although it is to be understood that the various instrumentalities of which the invention consists can be variously arranged and organized and that the invention is not limited to the instrumentalities as herein shown and described.

Referring to the accompanying drawings where like reference characters refer to like parts:

Figure 1 represents a perspective view of one form of infant's potty-chair incorporating the novel features of the present invention.

Figure 2 represents a vertical cross-sectional view generally along the lines 2—2 of Figure 1, but showing the deflector and seat-cover in lowered position (with the raised-portion of each shown in dash-dot lines).

Figure 3 represents a partial vertical cross-sectional view also generally along the lines 2—2 of Figure 1 but on an enlarged scale.

Figure 4 represents a partial vertical cross-sectional view generally like that of Figure 3 but showing a modification of the present invention.

Figure 5 represents a perspective view of the splash-shield or deflector, and the support therefor, shown in Figure 4.

Figure 6 represents a vertical cross-sectional view generally along the lines 6—6 of Figure 2.

Figure 7 represents a perspective view of the hinge-portion on an enlarged scale, of the deflector and support embodied in Figures 1, 2 and 3.

Figure 8 represents a vertical cross-sectional view, on a still larger scale, of the hinge and spring-portion of the deflector and support disclosed in Figures 1, 2, 3 and 7.

Referring now to Figure 1, an infant's potty-chair 20 including legs 21, back 22, arms 23 and swingable armrest or table 24 has a seat 25 in which a more or less conventional opening 26 appears. An edge 26-a of the opening 26 is generally circular or oval, or shaped so as to conform to toilet-seats designed for adults, but on a much reduced scale so as to be adapted for use by infants too small, or too immature, to use an adult-size toilet-bowl. The edge 26-a is preferably a continuous circle or curve, without any opening in the periphery thereof, particularly in the front, as at 27.

Disposed beneath the seat 25, and within the confines of the legs 21, is a bowl or receptacle 28, which has a diameter generally in excess of the greatest dimension across the opening 26. The container 28 also has a flange 29 adapted to engage a pair of grooved guides 30 disposed on the underside of the seat 25.

As is shown particularly in Figures 2 and 6, the guides 30 are adapted to support the container 28 closely adjacent the underside of the seat 25 in such a manner that no gap or space appears between the seat and the container. Such construction is highly desirable for purposes of improved sanitation, reduction in size of the chair, and ease in handling the entire potty-chair combination.

A handle 31 on the container 28 permits easy removal of the container 28 from the guides 30 and the chair 20 after the potty-chair has been used.

In addition, a seat-cover 32 is pivotally or swingably attached to seat 25 by a pair of hinges 33, so positioned, adapted and designed as to permit the seat-cover 32, in its lower position, to completely conceal the opening 26 in the seat 25, and in its upper or raised position to provide a comfortable, inclined backrest for the infant when seated upon the chair.

At the front of the opening 26, generally in the area indicated at 27, a splash-shield or deflector 34 is mounted upon the seat 25, closely adjacent the edge 26-a.

The splash-shield 34 generally consists of a concave cup-shaped bowl or deflector 35 having one edge 36 pivotally secured to a support 37.

The cup 35 may be constructed of various materials such as wood or rubber, but preferably is made of a molded synthetic resin. Likewise, the support 37 also may be made of wood or metal or synthetic resin or any other convenient or available material.

One end 38 of the support 37 is adapted to cooperate with the edge 36 of the cup 35 so that the cup 35 may pivot in relation to the support 37. This support 37 may be provided with a series of holes 39 whereby the support 37 may be affixed to the seat 25 and more particularly to the edge 26-a of the seat 25.

The support 37 preferably is shorter in length than the cup 35, and is adapted to be secured to the edge 26-a of the seat 25 in such a manner that the upper edge 40 does not project beyond the top surface of seat 25 and also in such a manner that the lower hinged-edge of the support 37 does not project beneath the undersurface of seat 25. This construction is shown more particularly in Figure 3. In this fashion the elements of the splash-shield do not project beneath the seat 25, providing uninterrupted insertion and removal of the container 28 with the edge 29 in contact with the underside of seat 25.

A number of screws 41 may be used to fasten

the support 37 to the seat 25 through the holes 39. However, I do not mean to limit myself to the use of screws as fastening devices since the support 37 may be fastened to the seat 25 in any one of the many well-known methods used for securing two items together.

As is disclosed more clearly in Figures 7 and 8, the lower edge 36 of the cup 35 may be broken away as at 42 so as to provide two hinge portions 43 adapted to receive the pin 44 and also adapted to receive therebetween a torsion spring 45. With particular reference to Figure 8, the spring 45 may have one end 46 adapted to bear against the lower edge of the cup 35 and its other end adapted to bear against the support 37. In this manner an automatically elevating device is provided for the cup 35 whereby said cup will rise to its operative position without being touched by the hands.

With reference to Figures 1, 2 and 3, the cup 35 is disposed and may be attached to the edge 26-a in such a manner that the cup 35 will be urged by the spring 45 into an upright position (shown in solid lines in Figure 1 and in dash-dot lines in Figure 2) when the seat-cover 32 is raised from the seat 25. Conversely, the seat-cover 32 will retain the cup 35 in a lowered position (shown in solid lines in Figure 2) when the said seat-cover is in lowered position. Thus, to close the potty-chair, it is necessary only to press against the back of cup 35 so as to pivot the cup 35 downwardly and inwardly about the pin 44, forcing it into the opening 26 and lowering the seat-cover 32. Although the spring 45 is strong enough to lift the cup 35 into upright position, it is not strong enough to overcome the weight of seat-cover 32 when the cover is lowered. However, when the seat-cover is raised, for use, the cup 35 will immediately spring into operative position.

Of particular importance is the design of the support 37 which permits the container 28 to slide along the guides 30 directly adjacent the underside of the seat 25 without striking or contacting any part of the support 37 or the hinge-members 38 or 43.

An alternative construction is disclosed in Figures 4 and 5 wherein the lower edge 36 of the cup 35 is not cut away (as at 42 in Figure 5) but which serves as a continuous bearing for the pin 44. In this modification the support 37-a extends above the upper surface of the seat 25 in such a manner that the screws 41 are adapted to enter the seat 25 from the upper surface rather than from the edge 26-a.

A tab 47 on support 37-a is adapted frictionally to engage a hole 48 in the cup 35. Thus, the tab 47 may be slightly tapered so that frictional engagement between the tab 47 and the hole 48 will retain the cup 35 in elevated position when the cup is raised and positioned for use.

However, either the modification shown in Figs. 1, 2 and 3, or the modification of Figs. 4 and 5 is adapted to be concealed beneath the seat-cover 32 when not in use. In the modification of Figures 4 and 5, the cup 35 is not automatically elevated to operative position but will be manually raised so as to engage the tab 47 in the hole 48. The constructions of Figures 4 and 5 dispenses with the necessity of spring 45 and, therefore, provides a less expensive method of constructing a disappearing splash-shield; but it is necessary to have the cup 35 in elevated position when inserting or removing the container 38 so as to prevent damage to said cup.

The cup 35, in either the manually-operable modification or the spring-urged modification, is entirely concealed within the confines of the potty-chair when the chair is not in use. Thus there is provided a neat and sanitary device which is adapted to assist youngsters in the use of a toilet-bowl, but which has no unsightly appearance when the chair is not being used by an infant.

I have thus shown and disclosed a potty-chair designed to permit its use by infants without any aid or assistance by adults. The potty-chair embodying the present invention is made instantly available for youngsters without the necessity of depending upon the assistance of their parents or other adults.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, what I claim as new and desire to protect by Letters Patent is:

1. A splash-shield for use on the front of an opening in the seat of an infant's potty-chair, comprising a hinged support adapted to be secured to the seat of the potty-chair near the front of the opening therein, and a deflector hingedly secured at one end thereto so that when said support is operatively secured to said seat the deflector may be moved through the opening of the seat, frictional retaining means on said support and frictional retaining means on said deflector adapted to cooperate with said frictional retaining means on said support when

said deflector is in its operative position whereby said deflector may be held in its operative position against said support, said support and said deflector being so disposed that when said deflector is in its upstanding operative position no part of said deflector or said support projects substantially beneath the bottom-most surface of said seat.

2. A splash-shield for use on the front of an opening in the seat of an infant's potty-chair, comprising a hinged support adapted to be secured to the seat of the potty-chair near the front of the opening therein, and a deflector hingedly secured at one end thereto so that when said support is operatively secured to said seat the deflector may be moved downwardly into the opening of the potty-seat, and means on said support for limiting the upward swinging of the deflector, frictional retaining means on said support and frictional retaining means on said deflector adapted to cooperate with said frictional retaining means on said support when said deflector is in its operative position whereby said deflector may be held in its operative position against said support, said support and said deflector being so disposed that when said deflector is in its upstanding operative position no part of said deflector or said support projects substantially beneath the bottom-most surface of said seat.
